Mason Fenwick Lawrence
Attorneys

UNITED STATES PATENT OFFICE.

THOMAS R. CARSON, OF SAN DIEGO, CALIFORNIA.

OIL-WELL PUMP AND FLOWING DEVICE.

Application filed September 4, 1924. Serial No. 735,966.

To all whom it may concern:

Be it known that I, THOMAS R. CARSON, a citizen of the United States, residing at San Diego, in the county of San Diego and State of California, have invented a certain new and useful Oil-Well Pump and Flowing Device, of which the following is a specification.

This invention relates to a device for use 10 in connection with oil wells and more particularly in connection with oil wells in fields where the gas pressure may be utilized in connection with suitable apparatus for elevating the oil a substantial height in the 15 casing.

In practice it is found that frequently the gas pressure is sufficient to raise the oil a substantial amount, but not sufficient to raise the oil to the top of the well, and the 20 present invention is directed to an improved structure, by means of which the oil may be raised to the surface in such cases.

A further object is the provision of means by which oil partially raised in the well by 25 gas pressure may be raised the balance of the way independently of and free from any gas.

Further objects will more particularly appear in the course of the following description.

The present invention consists in the novel construction, arrangement, and combinations of parts as hereinafter more particularly described and claimed.

One sheet of drawings accompanies this 35 specification as part thereof, in which like reference characters indicate like parts throughout.

The single figure shown is a vertical cross 40 sectional view through a section of an oil well casing, illustrating the application of the present invention.

In accordance with the present invention as illustrated, in a well casing 1 is positioned 45 a tube 2 through which the oil is to be drawn from the well. 3 indicates a packer secured to close casing 1 except for the passage through tube 2. Packer 3 as illustrated corresponds to the packer in the gas pressure 50 hydraulic elevator now in common use. Above packer 3 a second packer 4 is positioned upon plate 2, and preferably upon the top of packer 4 is secured a bucket 5 adapted to receive deposits of sand, etc.

Above packer 4 tube 2 is provided with 55 a plurality of transverse holes 6, and above

holes 6 a plug 7 is positioned in the bore of tube 2.

Above plug 7 tube 2 is provided with one or more radial internally threaded bores 60 adapted to receive an angle coupling 9 connected with a downwardly directed tube 10, the lower end of which extends adjacent the top of packer 4 and within bucket 5. Any number of such tubes may be used as 65 desired. Above coupling 9 a valved piston 11 is positioned within the bore of tube 2 adapted to operate as a lifting pump.

In operation tube 2 with the structure 70 previously described is lowered into the well casing 1 until packer 3 reaches substantially the height in the casing to which the gas pressure within the well will elevate the oil, this point being predetermined and the plug 7 so arranged within tube 2 that the bottom of the latter will extend as usual to the bottom of the well. It will be apparent 75 that the gas pressure will raise the oil in tube 2 and discharge the same through orifices 6 whence it will drop into bucket 5 and thence be raised by means of pump piston 11 operating in pipe 2 for drawing the oil from bucket 5 through downwardly directed pipe 10. The gas will flow upwardly through casing 1 and be discharged 80 at the top of the casing, while by reason of plug 7 only oil will be raised by pump 11.

Having thus fully described my invention, I claim:

1. In an oil well having a casing, a tube, 90 a packer mounted upon the tube and adapted to operate as a closure between the tube and the casing, said tube provided with a vent above the packer, a second tube extending 95 from adjacent the top of the packer and communicating with the first tube above said vent, and a lift piston operating in the first mentioned tube above the point of connection of the second mentioned tube.

2. In an oil well having a casing, a tube, 100 a packer positioned upon the tube adapted to operate as a stopper between the tube and the casing, a bucket secured upon the top of the packer, said tube provided with a vent above the packer, a second tube extending 105 from a point within the bucket adjacent the top of the packer and communicating with the first mentioned tube above said vent, and a lift piston positioned within the first mentioned tube above its connection 110 with the second mentioned tube.

3. In an oil well having a casing, a tube,

- a packer mounted upon the tube adapted to operate as a closure between the tube and the casing, a bucket mounted upon the top of the packer, said tube provided with a vent above the top of the packer, a plug in the tube positioned above said vent, a second tube extending from within the bucket adjacent the top of the packer and communicating with the tube above the plug in said tube, and a lift piston within the first mentioned tube above its point of connection with the second mentioned tube.
4. An improved oil lifting device comprising in combination a tube, a packer carried by the tube adapted to operate as a closure

between the tube and the casing of an oil well, a bucket mounted with its bottom adjacent the packer, said tube having a vent space above the bucket, a plug within the tube above the vent, an auxiliary tube extending from within the bucket adjacent the packer and communicating with the tube above the plug, and a lift piston operable within the tube above the latter's junction with the auxiliary tube.

20

25

In testimony whereof, I have hereunto set my hand at San Diego, California, this 30th day of August, 1924.

THOMAS R. CARSON.
